S. N. BUNNELL,
CLOTHES LINE STRETCHER,
APPLICATION FILED AUG. 10, 1915.

1,158,172.

Patented Oct. 26, 1915.

UNITED STATES PATENT OFFICE.

SAMUEL N. BUNNELL, OF TOMS RIVER, NEW JERSEY.

CLOTHES-LINE STRETCHER.

1,158,172.

Specification of Letters Patent. Patented Oct. 26, 1915.

Application filed August 10, 1915. Serial No. 44,713.

To all whom it may concern:

Be it known that I, SAMUEL N. BUNNELL, a citizen of the United States, residing at Toms River, in the county of Ocean and State of New Jersey, have invented certain new and useful Improvements in Clothes-Line Stretchers, of which the following is a specification.

The present invention relates to a clothes line stretcher, and has for its object to provide a device of this character which will eliminate the necessity for employing props to lift the clothes line after the clothes have been applied thereto, and which embodies novel features of construction whereby the line may be readily tightened so as to remove all slack therefrom and lift the clothes well above the ground.

Further objects of the invention are to provide a clothes line tightener which is comparatively simple and inexpensive in its construction, which can be readily applied as an attachment to a clothes line post, which can be easily and quickly manipulated to tighten or loosen the line as may be desired, which can be locked in an adjusted position, and which will not injure the line or interfere with hanging the clothes thereon in any manner.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a clothes line tightener constructed in accordance with the invention, showing the same as mounted upon a clothes line post and in engagement with a clothes line. Fig. 2 is a view of the upper end of the post upon which the clothes line tightener is mounted, looking at the same from a position at right angles to that of Fig. 1. Fig. 3 is a top plan view of the device. Fig. 4 is a horizontal sectional view on the line 4—4 of Fig. 2, looking in the direction of the arrows. Fig. 5 is a side elevation of the upper end of the device, with portions broken away and shown in section to illustrate more clearly the details of construction.

Corresponding and like parts are referred

to in the following description and indicated in all the views of the drawing by the same reference characters.

Referring to the drawings, which illustrate one embodiment of the invention, the numeral 1 designates an ordinary clothes line which is connected at its ends to suitable supports such as the post 2. Arranged at an intermediate position between the end posts 2 is a center post 3 upon which the line tightening mechanism is mounted. An upper bearing bracket 4 is applied to the top of the center post 3, while a similar bearing bracket 5 is let into and secured to the post at a point under the upper bracket 4. A vertical shaft 6 is journaled within the two bearing brackets 4 and 5 and has spaced relation to the post, the upper extremity of the shaft projecting above the bracket 5 and the top of the bracket being flush with the upper end of the post.

Removably applied to the upper extremity of the shaft 6 is a spherical head or ball 7, the base of the spherical head being slightly flattened so as to rest upon the top of the bracket 4, while a pair of diverging arms or fingers 8 project upwardly from the top of the spherical head. Corresponding lateral openings are provided in the spherical head 7 and the upper end of the vertical shaft 6 for the reception of a pin 9 which removably and detachably connects the spherical head to the shaft.

Keyed upon or otherwise made rigid with the lower end of the vertical shaft 6 is a toothed wheel 10 which rests upon the upper surface of the lower bearing bracket 5. The lower bracket 5 is shown as having an integral upward extension 11 which is let into the side of the center post 3 with its rear face flush with the rear face of the bracket 5, said extension having a pair of vertical swinging pawls 12 pivotally mounted upon the opposite sides thereof. Either one of these pawls can be swung downwardly into a horizontal position so as to engage the teeth of the wheel 10 and cooperate therewith to lock the vertical shaft 6 against rotation. The device may thus be held in an adjusted position, although by swinging both of the pawls 12 up into a vertical position, the shaft 6 may be rotated to tighten or loosen the clothes as desired.

Rigid with the toothed wheel 10 and surrounding the vertical shaft 6 is an upwardly

projecting polygonal boss or collar 13. A corresponding polygonal ring 14 fits removably upon the polygonal collar 13 and is provided with a lateral stem 15 adapted to 5 be detachably engaged by one end of a tubular handle 16. When not in use, the tubular handle 16 can be removed from the stem 15 and suspended upon the post 3 in some suitable manner. In the present instance the 10 tubular handle has a tapered formation and is adapted to be engaged by an eye 17 projecting laterally from one side of the post. The polygonal ring 14, as indicated by dotted lines on Fig. 2, can be readily lifted 15 above the polygonal collar 13 and rotated independently thereof, thereby enabling the ring to be brought into engagement with the polygonal collar with the lever or handle in a different position.

20 The two diverging arms 8 which project upwardly from the spherical head 7 at the top of the vertical shaft 6 provide a fork for the reception of an intermediate portion of the clothes line 1. Sufficient slack is initially allowed in the clothes line so that it will sag in the desired manner when applying clothes to the line or removing them therefrom. After the clothes have been applied to the line, the operator fits the handle 16 on the stem 15 of the polygonal ring 14 and by bringing the same successively into engagement with the polygonal collar 13 is enabled to rotate the shaft 6 and swing the line 1 around the prongs or arms 8 30 so as to take up the slack in the line. After the line has been thus tightened, one of the pawls 12 can be swung downwardly into engagement with the toothed wheel 10 so as to lock the vertical shaft 6 against backward rotation. The clothes are thus lifted well above the ground, without the necessity of using any props, and when it is desired to remove the clothes the line is unwound from the prongs 40 45 8 at the top of the spherical head 7 by exactly the reverse of the above described operation. The outer sides of the prongs or arms 8 converge downwardly toward the top of the spherical head 7 so that the tension produced in the line 1 will tend to force the portions of the line wound around the prongs downwardly upon the head. The spherical head 7 itself provides a large base to support the portions of line which may 50 55 be wound upon the prongs, and all sharp

angles or corners upon which the line might catch when revolving the vertical shaft are avoided. There is thus little danger of the line slipping over the upper ends of the prongs 8 when the device is being operated, 60 and the convolutions of the line about the prongs are supported in such a manner that they will not rub against a fixed vase or bracket and be subjected to unnecessary wear. By removing the spherical head 7 65 from the upper end of the vertical shaft 6, the lower end of the shaft may be lifted out of engagement with the lower bracket 5, and the shaft then tilted at a slight angle and drawn downwardly out of engagement with 70 the upper bracket 4. The device can thus be easily and quickly dismounted at any time when such may become desirable.

Although the line tightener has been described as applied to a post so as to engage 75 an intermediate point in the line, it will be understood that the line tightener may be applied to a house or other support at the end of the line, if desired.

Having thus described the invention, what 80 I claim as new and desire to secure by Letters Patent, is:—

1. A clothes line tightener including a vertical shaft, supporting bearings for the shaft, a head at the upper end of the shaft, 85 a pair of prongs projecting upwardly from the head and adapted to receive the clothes line between the same, means for rotating the shaft to wind the clothes line around the prongs and take up the slack therein, and 90 means for locking the shaft against backward rotation.

2. A clothes line tightener including a vertical shaft, supporting bearings for the shaft, a spherical head applied to the upper 95 end of the shaft, a pair of spaced prongs projecting upwardly from the top of the spherical head and adapted to receive the clothes line between the same, means for rotating the shaft to wind the clothes line 100 about the prongs, the portion of the line wound around the prongs resting upon the spherical head, and means for locking the vertical shaft against backward rotation.

In testimony whereof I affix my signature 105 in the presence of two witnesses.

SAMUEL N. BUNNELL.
